UNITED STATES PATENT OFFICE.

JOHN J. DALY, OF PHILADELPHIA, PENNSYLVANIA.

WATER-CLOSET.

1,294,421.

Specification of Letters Patent. Patented Feb. 18, 1919.

Application filed January 15, 1914. Serial No. 812,193.

To all whom it may concern:

Be it known that I, JOHN J. DALY, a citizen of the United States, and a resident of the city of Philadelphia, State of Pennsylvania, have invented certain new and useful Improvements in Water-Closets, of which the following is a specification, reference being had to the accompanying drawings.

The main object of this invention is to provide in a water closet a stool of improved construction in combination with a floor pipe or discharge pipe of improved construction, whereby all leakage of gas between the stool and floor pipe is prevented by a liquid seal which is renewed at each operation or flushing of the stool.

A further object of this invention is to provide an improved connection between the stool and the floor pipe, whereby the pipe is rotatively adjustable with respect to the stool and may be secured to the stool at any point in the rotation of the pipe.

Further objects of this invention will appear hereinafter.

In the accompanying drawings, Figure 1, is a vertical central section of a closet constructed in accordance with this invention; Fig. 2, a fragmentary top plan view of the same; Fig. 3, a horizontal section of the same on line 3—3 of Fig. 1; Fig. 4, a bottom plan view of the stool; Fig. 5, a top plan view of the discharge pipe; Fig. 6, a fragmentary vertical section of a modified form of this invention; and, Fig. 7, a fragmentary top plan view of the parts shown in Fig. 6.

Referring to the drawings, one embodiment of this invention shown therein comprises a stool 10 made of porcelain or other suitable material and provided with a base 11 preferably integral therewith adapted to rest upon a floor 12, and to be secured thereto in any suitable manner. The stool 10 comprises a bowl 15 which is surrounded along its upper margin by an internal annular conduit 16 provided with a series of outlets 17 for discharging water into the upper portion of the bowl. The conduit 16 communicates with an inlet compartment 18 arranged in the rear upper portion of the stool and having an inlet 19 which communicates through a supply pipe 20 with the usual tank (not shown) or other means for supplying water at intervals to the compartment 18 for flushing the closet. The inlet compartment 18 is provided with a

substantially horizontal bottom wall 25 and serves as an immediate reservoir or source of water supply for the closet.

The lower portion of the bowl 15 is provided with an inclined inlet 26 supplied with water by a pipe 27 inclined upwardly from a point beneath the inlet 26 and communicating at its upper end with the inlet compartment 18 through a suitable aperture 65 in the partition 25.

The stool 10 comprises suitable internal walls 30 forming in combination with the walls of the bowl 15 a siphon discharge duct 31 having at its upper end an inlet 32 communicating with the lower portion of the bowl 15, and at its lower end an outlet 34 formed by a tubular projection 35 depended downwardly from and preferably integral with, the base 11 of the stool, and extending through the floor 12. The tubular projection 35 is provided with a preferably integral tubular extension 36 depending downwardly therefrom, and of substantially the same external diameter as, but of greater 80 internal diameter than, the tubular projection 35. The tubular projection 35 is preferably provided at its lower end with a downwardly depending internal marginal integral lip 37 forming with the internal 85 surfaces of the projection 35 and the extension 36 an internal downwardly facing annular recess 38 in the lower end of the projection 35.

Depending downwardly below the stool 90 10 is a discharge pipe 40 communicating with the outlet 34 of the discharge duct, and having a preferably substantially uniform internal diameter slightly greater than the diameter of the outlet 34. The discharge pipe 40 is provided with an upper substantially vertical cylindrical inner tubular portion 41 surrounded by, coaxial with, and spaced from the tubular extension 36 and having its upper edge 42 engaging 100 in and spaced from the walls of the annular recess 38 and in a horizontal plane slightly below the horizontal plane of the lower edge of the lip 37. The discharge pipe 40 is also provided with an outer tubular substantially 105 cylindrical wall 43 surrounding and coaxial with the upper portion of the discharge pipe, and surrounding and spaced from the tubular projection 35 and its extension 36. This outer wall 43 is connected to the body 110 of the discharge pipe 40 as at 44 in a substantially horizontal plane slightly below

the lower edge of the tubular extension 36, and is provided at its upper edge with an outwardly extending flat annular flange 45 which engages against the under surface of 5 the base 11 of the stool 10 in an annular recess 46 provided therefor in the under side of the base. The discharge pipe 40 thus forms in combination with the tubular projection 35 and tubular extension 36 of 10 the stool 10 a trap-shaped passage 47.

For clamping the discharge pipe 40 securely in any desired position of rotary adjustment with respect to the stool 10, an annular clamping plate 50 is arranged loosely 15 within the annular recess 46 and is provided with an internal flange 51 which engages against the under surface of the flange 45 of the discharge pipe. This clamping plate 50 is arranged to be drawn upwardly to clamp 20 the flange 45 of the discharge pipe 40 against the corresponding flat under surface of the base 11 by means of two or more bolts 52 extending loosely through apertures provided therefor in the base 11, and threaded 25 at their lower ends into the annular clamping plate 50, each bolt 52 being provided at its upper end with a head 53 of hexagonal or other suitable shape.

An annular gasket 55 of rubber or other 30 suitable material may be arranged between the base 11 and the flange 45 in suitable co-operating annular recesses 56 and 57 provided therefor in the under surface of the base 11 and the internal marginal portion of 35 the flange 45 to prevent leakage between the stool 10 and the discharge pipe 40. This gasket 55 surrounds and is in contact with the outer cylindrical surface of the tubular projection 35 and forms a closure for the 40 upper end of that portion of the trap-shaped space 47 which lies between the outer surface of the tubular projection 35 and the inner surface of the outer tubular wall 43, the gasket being normally held in a compressed state by the clamping action of the 45 flange 45. Prior to this invention it has been customary to insert a rubber gasket between the stool and the discharge pipe to prevent leakage of gas or water, but it has been 50 found in practice that such a gasket is apt to gradually deteriorate and to eventually be insufficient to prevent this leakage. The present invention uses this gasket only as an auxiliary means and provides a liquid 55 seal between the stool and the discharge pipe, as will appear hereinafter, and thus provides means which will prevent any leakage during an indefinite period of use. Thus the rubber gasket 55 being only an additional means for preventing leakage might 60 be omitted without rendering the device subject to leakage under ordinary conditions of use.

For injecting water into the trap-shaped 65 space 47 between the stool 10 and the dis-

charge pipe 40 as a result of the admission of water into the inlet compartment 18 of the stool, a plurality of apertures 65 converge upwardly and inwardly from that portion of the trap-shaped space 47 which 70 lies between the tubular projection 35 and the outer tubular wall 43 and communicate at their upper ends with an annular passage 66 which surrounds the lower portion of the siphon discharge duct 31 being formed by a 75 partition 67 integral with the stool 10 and extending from the upper surface of the base 11 to the wall 30 of the siphon duct 31. This annular passage 66 communicates with the lower portion of a space or passage 68 between the wall 30 of the siphon duct 31, the rear wall 69 of the stool, and which passage extends upwardly and communicates at its upper end, through a plurality of apertures 70 through the partition 80 25, with the inlet compartment 18, and also communicates at its upper end through a branch passage 71 with the upper portion of the interior of the bowl 15, this branch passage serving as an air vent for the air displaced by the water in falling through the 85 passage 68. The converging apertures 65 are preferably spaced uniformly and arranged in radial planes around the vertical axis of the tubular projection 35, the sum of the 90 cross-sectional areas of these apertures being preferably slightly greater than the sum of the cross-sectional areas of the apertures 70 through the partition 25, so as to provide a free passage of the water into and through 100 the trap-shaped space 47 to prevent an excessive accumulation or backing up of the water in the passages 66 and 68 of the stool 10.

An aperture 75 is arranged through the rear wall 69 of the bowl and in horizontal 105 and axial alignment with the annular passage 66 surrounding the lower portion of the siphon duct 31 to permit of the convenient cleaning of this annular passage and the passage 68 leading upwardly therefrom. 110 This aperture 75 is normally closed by any suitable removable plug 76.

The construction of this closet is such that when the usual predetermined amount of water is allowed to flow into the inlet 115 compartment 18 of the closet through the supply pipe 20 by the manual operation of a valve (not shown) in a well-known manner, a portion of this water will flow around the annular conduit 16 and through the 120 openings 17 into the upper part of the bowl 15, while another portion of the water will flow downwardly through the pipe 27 and pass upwardly through the opening 26 in the form of a siphon jet, and a third portion 125 will pass downwardly through the openings 70 into the passage 68 and then through the annular passage 66 and aperture 65 into the trap-shaped space 47 between the stool 10 and the discharge pipe 40. The water 130

passages between the inlet compartment 18 and the trap-shaped space 47 are so designed as hereinbefore described, that the water will not rise in the trap-shaped passage 47 much above the lower ends of the apertures 65 and will at no time reach the level of the gasket 55 but will pass downwardly from the lower ends of the apertures 65 and around the lower end of the tubular extension 36 thence upwardly between the tubular extension 36 and the inner tubular portion 41 of the discharge pipe 40, inwardly over the upper end of the tubular portion 41 and downwardly through the space between the upper edge of the tubular portion 41 and the lower edge of the lip 37 into the upper end of the discharge pipe 40. This passage of the water from the trap-shaped space 47 into the discharge pipe 40 is facilitated by the action of the water simultaneously passing downwardly through the outlet 34 of the siphon duct 31 which tends to create a partial vacuum in the trap-shaped passage 47 in a manner analogous to the action of the well-known Sprengel air pump. After the inlet compartment 18 has been entirely emptied of water and that portion of the water which has passed through the aperture 70 has all passed downwardly through the apertures 65 and into or through the trap-shaped space 47, a portion of this water will remain therein to form a liquid seal between the stool 10 and the discharge pipe 40, this water forming the seal being renewed or replaced by fresh water each time that the closet is operated or flushed as hereinbefore described. This liquid seal between the stool 10 and the discharge pipe 40 acts to positively and absolutely prevent any escape of gases, either noxious or otherwise, into the atmosphere through the joint formed between the stool 10 and the discharge pipe 40, while the renewal of the water seal at the trap at each flushing or operation of the closet prevents the seal from becoming contaminated and, therefore, is advantageous; but it is evident that in the construction of this closet the passages 65, 66, 68, and 70 provided for the renewal of the seal, might be omitted and a permanent liquid seal of water or mercury or any other suitable liquid might be arranged in the trap-shaped passage 47 to perform the function of preventing the escape of gases through the joint between the stool 10 and the discharge pipe 40.

Instead of clamping the discharge pipe 40 to the stool 10 by means of an annular clamping plate 50 and bolts 52, the annular clamping plate 50 may be omitted and the flange 45 of the discharge pipe 40 provided with a large number of threaded apertures 80 and the discharge pipe 40 may then be clamped in any desired position of rotary adjustment by means of two diametrically

opposed bolts 81 extending downwardly through slightly elongated arcuate recesses 82 provided therefor through the base 11, as shown in Figs. 6 and 7 and at points corresponding to the location of the bolts 52, 70 shown in Figs. 1 and 3, only one of the bolts 81 being shown in Figs. 6 and 7.

It will be evident that this change in the construction as well as various other changes may be made in applying the invention, and 75 that the invention may be readily adapted either to various forms of closets such as are now in general use or to any suitable form which may be devised. It will also be evident that instead of leading the water 80 through the stool and into the trap through the form of passage shown, it may be carried into the trap through any other suitable passage either through the stool or otherwise. Furthermore, although only two 85 embodiments of the invention have been herein illustrated and described it is not thereby intended or desired to limit the invention to any specific construction as it may be readily applied in various other 90 forms without departing from the spirit or scope of the invention as defined in the appended claims.

Having thus fully described this invention I claim and desire to protect by Letters 95 Patent of the United States:

1. In a water closet the combination with a stool comprising a bowl and a discharge duct leading from said bowl, said stool being provided with a passage surrounding said 100 duct, of a discharge pipe arranged beneath said stool and detachably connected thereto and forming therewith a trap-shaped passage communicating with said first mentioned passage by a plurality of upwardly 105 extending apertures and with the interior of said discharge pipe, said stool being provided with self-contained means for admitting water into said first mentioned passage.

2. In a water closet the combination with a stool comprising a bowl, and a discharge duct leading from said bowl and said stool being provided with a passage surrounding said duct, of a discharge pipe arranged beneath said stool detachably connected thereto and forming therewith a trap-shaped passage communicating with said first mentioned passage and with the interior of said discharge pipe, said bowl being provided with means for admitting water into said first 120 mentioned passage and with an opening through an exterior wall thereof and in alignment with said first mentioned passage to permit of the cleaning of said first mentioned passage, and removable means normally closing said opening.

3. In a water closet the combination with a stool, of a discharge pipe arranged beneath said stool detachably connected thereto and forming therewith a trap- 130

shaped passage, said stool being provided with a plurality of apertures leading downwardly into said passage and a plurality of apertures arranged to supply water to said 5 first mentioned apertures.

4. In a water closet the combination with 10 a stool, of a discharge pipe arranged beneath said stool detachably connected thereto and forming therewith a trap-shaped passage, said stool being provided with a plurality of apertures leading downwardly into said passage and a plurality of apertures arranged to supply water to said first mentioned apertures, the sum of the cross-sectional 15 areas of said first mentioned apertures being greater than the sum of the cross-sectional areas of said second mentioned apertures.

5. In a water closet the combination with 20 a stool provided with an outlet, of a discharge pipe arranged beneath said stool and detachably connected thereto in communication with said outlet and forming with said stool a trap-shaped passage, said stool being provided with a plurality of apertures leading downwardly into said trap-shaped passage, and means having a total 25 cross-sectional area for the passage of water

less than the sum of cross-sectional areas of said apertures for supplying said apertures with water. 30

6. The combination with a stool, of a discharge pipe detachably connected thereto, 35 said stool comprising a bowl having a discharge duct provided with an outlet opening into said discharge pipe, and said discharge pipe forming with said stool a trap-shaped space arranged to contain a water seal and having an outlet communicating with the interior of said discharge pipe, an 40 inlet pipe, and a conduit for simultaneously supplying said bowl and trap-shaped space respectively with water from said inlet pipe, said bowl being provided with a plurality of passages leading into said trap-shaped space 45 and forming a part of said conduit whereby all of the water in said trap-shaped space is simultaneously flushed with said bowl.

In witness whereof I have hereunto set my hand this 13th day of January A. D., 50 1914.

JOHN J. DALY.

Copies of this patent may be obtained for five cents each, by addressing the "Commissioner of Patents, Washington, D. C."

It is hereby certified that in Letters Patent No. 1,294,421, granted February 18, 1919, upon the application of John J. Daly, of Philadelphia, Pennsylvania, for an improvement in "Water-Closets," an error appears in the printed specification requiring correction as follows: Page 2, line 4, after the word "against" insert the clause *a flat horizontal annular surface provided therefor in a plane spaced above the upper end 42 of the discharge pipe and upon*; and that the said Letters Patent should be read with this correction therein that the same may conform to the record of the case in the Patent Office.

Signed and sealed this 7th day of October, A. D., 1919.

[SEAL.]

M. H. COULSTON,

Acting Commissioner of Patents.
